CAM MAKING FIXTURE

Leonard H. Savage, Grandville, Mich., assignor
to Joseph P. Van Blooys, Grand Rapids, Mich.

Application June 16, 1947, Serial No. 754,838

2 Claims. (Cl. 90—11)

1

The present invention is directed to a fixture which is used in marking or scribing the outlines of cams or in finishing such cams, which are used in automatic screw machines for controlling the movements of tools in machining processes upon rotating stock, processed in said automatic screw machines or lathes.

The laying out and marking of the cam edges on a flat, usually circular plate or disk of metal, from which a cam is made, has previously been a long and tedious process, requiring a high degree of skill and knowledge in order to have the finished cam, which is produced, function properly in use. With the cam producing fixture which I have produced, cams may be marked and laid out or diagrammed on flat plates of steel or like material used in the cams, very readily and perfectly, in a short time and with accuracy. The high degree of skill and knowledge previously required is not required for successful utilization of the machine of my invention. Moreover, the invention which I have made may be embodied in a structure which is without complications or complexities of parts either in their fabrication, assembly or use; and is produced economically in a practical and serviceable form to attain the results which have been stated.

An understanding of the invention may be had from the following description, taken in connection with the accompanying drawings, in which,

Fig. 1 is a side elevation of the cam marker of my invention shown adjustably secured to the bed of the grinding machine,

Fig. 2 is an end elevation thereof, looking at the structure in Fig. 1 from the right,

Fig. 3 is a plan view,

Fig. 4 is a horizontal section and plan, substantially on the plane of line 4—4 in Fig. 1.

Fig. 5 is a transverse vertical section, and

Fig. 6 is a vertical side elevation of the upper part of the machine, with a modification in the mechanism used for machining the edge portions of the cam disk in the fixture without marking or scribing of the lines of the cam on the disk, the cam produced being that which in the structure shown in Fig. 1 marks or scribes, which is later completed by removing edge portions of the metal from the disk.

Like reference characters refer to like parts in the different figures of the drawings.

In Fig. 1, the bed or table 1 of the grinding machine, with a horizontal T-slot 2 therein, has the horizontal base 3 of the fixture of my invention located thereover, adjustably connected at said slot by use of T-bolts 4 in an old and well

2

known manner. At one edge portion of the base 3 a vertical support 5 is located and permanently secured at its lower edge. Said support, in the form generally of a rectangular heavy plate of metal, is slotted between its upper and lower edges from one vertical edge toward, but short of, the other edge (Fig. 2) as indicated at 6. At the upper edge of the support 5 a central vertical projection 7 is integrally formed, with a hole drilled therethrough and a slot leading from one edge of the projection to said hole, as shown in Fig. 2.

Two spaced cylindrical rods 8 are securely connected at one end to the support 5, and extend horizontally over the base 3 a distance thereabove. The rods 8 are below the slot 6 (Fig. 1). A second pair of identical horizontal rods 9, permanently connected to the support 5 and directly above the rods 8, extend in the same direction from the plate 5 in a plane above the slot 6. A table 10 is mounted for sliding movement on the rods 8, which pass therethrough, and is adjusted toward or away from the support 5 by a screw 11 threading into the table, turned by a handle 12 connected to the outer end portion of the screw (Fig. 4). At the edge of the table 10 nearest to the support 5, an indicator quadrant 13 is secured which, in a ninety degree arc thereof, is divided into a plurality of successive equal divisions forming a scale of degrees on the ninety degrees of the arc.

A somewhat elongated horizontal bar 14, of a generally short inverted T cross section (Fig. 1), is mounted, between its ends, to turn about the vertical axis of a pin 15 (Fig. 5), which is fixed to and extends upwardly from the table 10. A U-shaped stirrup 16 (Fig. 5) is secured to the under side of the guide bar 14 through which the quadrant scale 13 slidably passes, the center of curvature of the edges of said quadrant 13 being in the vertical axis of the pin 15. The bar may be fixed against turning movement at any place to which moved on the pin 15 by a thumb set screw 17 (Fig. 5), passing through the lower side of the stirrup 16 against the under side of the quadrant 13.

A block 18 is slidably mounted upon the bar 14 which guides it in its movement. A screw threaded rod 19 is threaded through block 18 at one side and lies alongside of and parallel to the guide bar 14, passing through a block 20 secured at the outer end of the guide bar 14. At the end of said rod, adjacent block 20, a crank 21 is fixed for turning the threaded rod to move the block 18 to different positions in the length

of the guide bar 14. A vertical pin 22 is fixed to and extends above the block 18 (Fig. 5) on which an elongated bar 23 is mounted, midway between its ends, to turn. It has a rack 24 at one side for its length. The bar 23 at its upper portions is received in a transverse slot in the under side of a rectangular carrier 25, slidably mounted on the upper rods 9. Near its side, farthest away from the support 5, a vertical spindle 26 is rotatably mounted, which at its lower end, immediately underneath the carrier 25, has a gear 27 fixed thereon in meshing engagement with the rack 24. Above the carrier 25 a small table 28 is secured, at the upper side of which a flat disk 29, from which a cam is to be made, is detachably located. The cam plates 29 used, each has an opening as at 29a (Fig. 3) for a pin on the table 28 to extend into and cause the plate 29 to turn with the table.

A rod 30 is clamped in the opening drilled through the projection 7, previously described, and extends over the edge portions of a disk 29. At its end over the plate, a holder 31 for a spring pressed scribing implement 32 is secured, the pointed hardened lower end of which bears with spring pressure against the upper side of the cam plate 29.

The gear 27, spindle 26, table 28 and the cam plate 29 are rotated by turning the crank 21, which simultaneously moves the block 18 and the bar and rack 23 and 24 in accordance with the angular position of the guide bar 14 with respect to the quadrant 13. If the bar 14 was turned from the position shown in Figs. 3 and 4 so as to be at right angles to the rods 8, there would be merely a rotation of the disk 29 without any body movement thereof toward or away from the support 5, as under such conditions the two pins 15 and 22 would be in direct alignment, and bar 23 and rack 24 move in the slot in the underside of the carrier 25 without a change of position of such carrier. If the bar 14 was at its other extreme position, paralleling the rods 8 and 9, rotation of the cam disk 29 would not take place, but it would be moved bodily toward or away from the vertical support 5 in accordance with the direction that the crank 21, turning the threaded rod 19, was rotated. At intermediate positions between the two extreme positions, there is a combined rotation of the cam plate 29 and a bodily movement as it moves with the carrier 25 on the rods 9. The extent of the bodily movement and also of the rotation of the cam disk varies in accordance with the angular position of the bar 14 with relation to the quadrant 13. Such combined rotation and bodily movement of the cam plate causes the scribing of a line on the upper side of the cam plate by the marking pin 32, thereby defining the outline of the cam desired and its progressive rise or lift from one end, where it is nearest the center of the plate or disk 29 to the other end, where it is farthest away.

After the cam outlined, or the peripheral edges thereof have been thus marked, the marked cam plate 29 is removed and the metal outside of the edges which it is to have, as defined by the marking, is ground away in rough grinding operations, leaving small portions of the plate beyond the scribed marking. It is then again put back on the fixture and the fixture properly adjusted with reference to a grinding wheel, indicated in dash lines at 32, and by properly operating the crank 21 the cam edge is ground to exactness.

In Fig. 6, a variation or modification in the

structure is shown. Instead of scribing or marking the lines to which the plate or disk 29 is to be subsequently ground, the cam is finished by the milling of the cam disk at its edges. A bracket 33 is secured at the upper part of the vertical support 5, on which a small electric motor 34 is mounted. Another bracket 35, as shown in Fig. 6, connected with the first bracket and with the motor casing carries a vertical rotating milling tool 36, continuously driven by the motor through the bevelled gearing at 37. As the cam disk or plate 29 is rotated and bodily moved with reference to the vertical milling tool, the metal at the edge portions of the cam is cut away in the desired amounts and in accordance with the selected position at which the bar 14 is set with reference to the quadrant 13, for the selected progressive degree of lift which is wanted in the particular cam which is being processed.

The invention disclosed is very practical and useful and results in a great saving of time and in better and more accurate cam production by operators less skilled than heretofore required.

The invention is defined in the appended claims and is to be considered comprehensive of all forms of structure coming within their scope.

I claim:

1. In a structure as described, lower horizontal carrying and guiding means, a table movably mounted thereon, means for adjusting said table to different fixed adjusted positions, an elongated bar member, a stud pivotally mounting said bar on and above the table for adjustability about a vertical axis located between the ends of the bar, means to secure said bar in adjusted position, an upper horizontal carrying and guiding means located in fixed position above the lower carrying and guiding means, a carrier slidably mounted thereon and having a downwardly facing slot extending transverse to said sliding movement, a vertical shaft rotatably mounted on the carrier, a gear fixed to said shaft, a support above said gear and rotatable with said shaft, said bar having track means extending lengthwise thereof, block means mounted on said bar and movable lengthwise thereof along said track, a rack bar meshing with said gear and mounted for sliding movement in the slot of said carrier, a vertical pin extending upwardly from said block means in spaced relation to the vertical axis of said stud and into said bar, manually operated means for sliding said block means lengthwise of the bar, whereby said vertical pin will move said rack to rotate said shaft and move said carrier to displace the axis of rotation of said shaft.

2. In a structure as described, a table, an elongated bar member, a stud pivotally mounting said bar on and above the table for adjustability about a vertical axis located between the ends of the bar, means for securing said bar in adjusted position, horizontal carrying and guiding means located in fixed position above the table, a carrier slidably mounted thereon and having a downwardly facing slot extending transverse to said sliding movement, a vertical shaft rotatably mounted on the carrier, a gear fixed to said shaft, a support above said gear and rotatable with said shaft, said bar having track means extending lengthwise thereof, block means mounted on said bar and movable lengthwise thereof along said track, a rack bar meshing with said gear and mounted for sliding movement in the slot of said carrier, a vertical pin extending upwardly from said block means in spaced relation to the vertical axis of said stud and into said bar, man-

ually operated means for sliding said block means lengthwise of the bar, whereby said vertical pin will move said rack to rotate said shaft and move said carrier to displace the axis of rotation of said shaft.
